UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 19,890, dated June 10, 1890.

Application filed May 14, 1890. Serial No. 351,816. Term of patent 14 years.

To all whom it may concern:

Be it known that I, GEORGE H. BABCOCK, a citizen of the United States, residing at Plainfield, in the county of Union and State of New Jersey, have invented and produced a new and original Design for Roofing or Sheathing Tiles, of which the following is a specification, reference being had to the accompanying drawing, forming a part thereof.

10 My design relates to the architectural ornamentation of clay or other tiles by raised figures upon the exposed face thereof, and also by the contour by which the face is bounded.

15 My design consists of a tile having a semicircular exposed face and the conjunction therewith of rays composed of raised ridges radiating from a prominent center.

20 In the drawing, A represents the plane surface of the tile, *a a* the upward flanges adapted to interlock with downward flanges *b b* of

adjacent tiles above, and *c* the semicircular periphery bounding the lower portion of the tile.

d is the raised center of the radiating figure, and *e* the rays thereof formed of raised ridges. The ridges *e* have rounded or bulbous terminations *f*, joined together by concave surfaces *g* between them, producing a scalloped effect around the semicircular periphery *c*.

25 30 What I claim is—

The design for a roof-tile herein shown and described, consisting in a semicircular radiating figure composed of ridges expanding from a raised center, in conjunction with a semicircular contour at the base of the tile.

35 GEO. H. BABCOCK.
